UNITED STATES PATENT OFFICE.

HERMAN J. RADEMACHER, OF MILWAUKEE, WISCONSIN.

DESIGN FOR A CASKET.

No. 39,042.

Specification for Design.

Patented Jan. 28, 1908.

Application filed December 4, 1907. Serial No. 405,126. Term of patent 3½ years.

To all whom it may concern:

Be it known that I, HERMAN J. RADEMACHER, a citizen of the United States, residing at Milwaukee, in the county of Milwaukee and State of Wisconsin, have invented a new, original, and ornamental Design for Caskets, of which the following is a specification, reference being had to the accompanying drawing, forming part thereof.

The figure is a front elevation of a casket, showing my new design.

I claim:

The ornamental design for a casket, as shown.

HERMAN J. RADEMACHER.

Witnesses:

LEO RADEMACHER,
BOYNTON LEACH.
